UNITED STATES PATENT OFFICE.

KENNET JOHN GIRDWOOD, OF MONTREAL, QUEBEC, CANADA.

PERCUSSION-FUSE.

1,224,631.

Specification of Letters Patent.

Patented May 1, 1917.

Application filed August 30, 1916. Serial No. 117,440.

To all whom it may concern:

Be it known that I, KENNET JOHN GIRDWOOD, a subject of the King of Great Britain, and a citizen of Montreal, in the Province of Quebec, Dominion of Canada, have invented certain new and useful Improvements in Percussion-Fuses, of which the following is a specification.

My invention relates to fuses adapted to be inserted into the points of high explosive shells to be shot from a cannon, and one of the main objects thereof is to provide such fuses which will cause the shells to explode if they graze an object enough to slightly retard their flight, as well as when the shells strike the ground or an object fairly to stop their flight.

A further object is to provide a graze and percussion fuse of simple design wherein special attention is given to the concentricity of the parts to simplify the balancing and manufacture.

A further object is to provide such a fuse which is normally locked against accidental actuation to explode the shell and which locking means are released by centrifugal force due to the rotation of the shell after being discharged from a cannon, after which the said locking means are rendered inoperative for a reason to be later explained.

A further object is to provide a plunger provided with a needle point and with passages leading rearwardly therefrom to allow the flash from the detonator to pass to the charge in the shell.

My invention is fully described in the following specification, of which the accompanying drawings form a part, in which like characters refer to like parts in each of the views, and in which:

Figure 1 is a fragmentary elevation of a shell provided with my invention, partly in central longitudinal section, with the parts in safety positions though ready for discharge from a cannon;

Fig. 2 is a detached view of a plunger which I employ; and

Fig. 3 is a detached view of one of the plunger locking bolts.

Referring to the drawings, 4 represents a fuse having a reduced rear end externally threaded at 5 for engagement with a shell 6, said rear end having an internally threaded recess 7 for a gaine 8, an internally threaded recess 9 for a plunger lock 10 provided with a magazine 11, a plunger cham-

ber 12, and a threaded recess 13 for a detonator 14 located well toward the point of the fuse, the screw threads in the recesses 7, 9 and 13 being left-handed in order to resist any unwinding of the connected parts by the rotation of the shell in flight.

Slidably mounted in the chamber 12 is a plunger 15 having a needle point 16 adapted to enter the detonator 14 and having passages 17 leading rearwardly from said needle point to an axial passage 18 for leading the flash of the detonator rearwardly to the charge of the shell, said plunger having two longitudinally arranged grooves 19 in its outer surface, diametrically arranged, and with an internally threaded recess 20 to be used in the assembling of the parts of the fuse with a special tool not illustrated, the plunger being kept from creeping forwardly by means of a light spring 21.

The fuse body 4 is provided with two diametrically and radially arranged chambers 22 for the reception and movement of plunger locking bolts 23 normally held in locking positions by means of springs 24 and screw threaded plugs 25, said bolts having, each, a spherical head 26 unbalanced by being cut away at one side and a reduced cylindrical member 27 normally held in a passage 28 in the body 4 and movable therein, this being an important feature of the fuse.

During the handing of a shell and its introduction into a cannon the springs 24 positively prevent outward movement of the bolts 23 out of plunger engagement and the latter cannot therefore move forwardly toward the detonator 14 even if the shell should fall upon its point, but these springs 24 do not possess sufficient strength to resist the outward bolt movement by centrifugal force in the rotation of the shell after discharge from the cannon.

Upon such discharge, the bolts 23 move outwardly by centrifugal force free from the cylindrical passages 28 and into the chambers 22 where, also by centrifugal force, the heavier side of the unbalanced bolts is drawn outwardly more than the lighter side and thus causes the bolts to tip toward the heavier side and lock themselves, no matter in what position they be placed in the chambers 22, the spherical heads permitting this movement, and no obstacle is thereafter presented to the forward movement of the plunger 15 other than the rela-

tively light spring 21 whose only function is to prevent the plunger from creeping toward the detonator during the flight of the shell.

- 5 If the shell should strike a glancing blow against an object or against the ground the resistance of the spring 21 will be overcome and the detonator exploded by the plunger 15, and this is obviously true if the shell 10 makes a solid impact against either an object or the earth, with the result that the shell will be exploded on what might be termed the "hair trigger" principle after leaving the cannon, although there is no 15 possibility of exploding the shell during the handling thereof.

If, for any reason, the centrifugal action on the bolts 23 should be prevented, the cylindrical portions 27 thereof would be 20 sheared off by the weight of the plunger 15 upon the impact of the shell with an object or with the ground after having been fired from a cannon, said portions 27 being made of such a relative diameter and of such material as to insure such shearing under these 25 conditions.

My fuse is very simple in construction and is perfectly balanced with respect to its axis, there are no indirect passages for 30 the detonator flash toward the charge in the shell, there is no possibility of relocking the plunger after it has been once unlocked as the bolts 23 are of sufficient weight to insure their outward movement against 35 the springs 24 in the shell rotation during flight, and there is no possibility of unscrewing the separable parts during the flight of a shell because of the reverse screw threads.

40 While I have shown a preferred embodiment of my fuse, I do not desire to limit myself to the exact details as many changes thereover might suggest themselves and still be within the spirit of the invention and the scope of the appended claims. 45

Having fully described my invention, what I claim as new, and desire to secure by Letters Patent, is:—

1. A percussion fuse, comprising a body having means for connection with an explosive shell, a detonator, a plunger, radially arranged bolts consisting of cylindrical members arranged in radial passages in said body and spherical heads arranged in enlarged radial chambers in said body, and springs for normally maintaining said cylindrical bolt members in engagement with said plunger to prevent movement of the latter toward said detonator, one side of each of said heads being cut away to destroy the balance thereof, said cylindrical members being adapted to be withdrawn from said passages by centrifugal force and said heads being turned with their heavier sides outwardly of said fuse by centrifugal force 65 to move the axes of said cylindrical members out of the axes of said passages to prevent the entry of said cylindrical members into said passages after having been drawn out of the same by centrifugal force. 70

2. As an article of manufacture, for use in a percussion fuse, a plunger locking bolt consisting of a cylindrical member and an enlarged spherical head cut away at one side to destroy the balance thereof.

KENNETH JOHN GIRDWOOD.
